UNITED STATES PATENT OFFICE.

THEODORE J. BARCK, OF QUINCY, WISCONSIN.

TIE-HOLDER.

1,095,781.

Specification of Letters Patent.

Patented May 5, 1914.

Application filed February 10, 1914. Serial No. 817,870.

To all whom it may concern:

Be it known that I, THEODORE J. BARCK, a citizen of the United States, residing at Quincy, in the county of Adams and State 5 of Wisconsin, have invented new and useful Improvements in Tie-Holders, of which the following is a specification.

This invention relates to tie holders; and it has for its primary object the provision 10 of a device of this character which is designed particularly for use in retamping the soil forming the road-bed on which a track structure is laid and for elevating the tie to restore the same to its proper seated 15 position against the rail and retain the tie in this position during the tamping operation and at the time of reforming the road-bed.

A further object of the invention is the 20 provision of a device of this character which may be operated for the specified purpose without necessitating the removal of the ties from the track.

A further object of the invention is the 25 provision of a supporting brace for holding the elevated member in an elevated position and the construction of the holding means which will obviate the necessity of an attendant holding the lever during the tamping 30 operation.

With these and other objects in view, the invention consists of certain novel features of construction, combination and arrangement of parts, as will be hereinafter described and claimed.

In the accompanying drawings:—Figure 1 is a perspective view, showing a rail extended over a plurality of ties and illustrating the application of the holder to one of 40 the ties and the manner of adjusting the holder so as to effect an elevated position of the tie under which it is desired to tamp the soil; Fig. 2 is a vertical longitudinal section of the holder, showing the support therefor; 45 and Fig. 3 is a perspective view of the gripping device.

The device is primarily intended to be used in the reconstruction or remodeling of road-beds and track-structures, and it aims

to provide means whereby a tie which has 50 become deranged from the rails, may be readjusted into proper position and elevated initially from the surface of the ground so that addition soil or ballast may be placed beneath the tie.

In view of the above the results desired 55 may be most satisfactorily accomplished through the provision of a lifting lever 1 bifurcated at one end to provide parallel branches 2, 2 that are adapted to rest on the ball of the rail, as shown in Figs. 1 and 2 during the operation of lifting the tie with 60 relation to the rail. The device is of a form that it may be so associated with the tie to be lifted that the space defined by the tie 65 to be lifted and the adjacent tie will not be obstructed by the device. The members or branches 2, 2 of the lifting lever are provided with integral lugs 3 that are adapted to engage against the adjacent side of the 70 ball of the rail so as to minimize the possibility of the lever slipping during the lifting operation. The lifting lever is provided with a pivoted gripping member 4 which is adapted to always assume a vertical position, and as shown said member is provided with a substantially stepped or offset 75 lower portion 5 having lateral branches 6, 6 that are adapted to engage beneath the tie as shown in Figs. 1 and 2.

In using the device for the purpose of 80 moving the same with relation to the rail during the time of tamping the soil beneath the deranged tie, the lifting lever is arranged so that the branches 2, 2 of the bifurcated portion thereof immediately rest against the ball of the rail. The tie raising member 4 is placed along one end of the tie to be lifted and the stepped lower portion thereof is engaged beneath the tie. The 85 free end of the lever is then moved in an upward direction, and as a consequence thereof the deranged tie will be moved in the direction of the base of the rail and the soil beneath the tie may be properly tamped 90 and the road-bed in this manner may be expeditiously remodeled or repaired. In order 95 to hold the lever in its adjusted position a

brace 7 which may be in the form of a crow-bar or tool commonly used in road-bed construction and connected with the lever as shown in Figs. 1 and 2.

5 I claim:—

A device of the character described comprising a lifting lever having a horizontal bifurcated end, the branches of which have

ing integral lugs, and a pivoted gripping device carried by the lever. 10

In testimony whereof I affix my signature in presence of two witnesses.

THEODORE J. BARCK.
